(57) **CLAIM**

The ornamental design for a multi-lifting cold and heat beauty device, as shown and described.

DESCRIPTION

FIG. 1 is a perspective view of a multi-lifting cold and heat beauty device showing my new design;

FIG. 2 is a front plan view thereof;

FIG. 3 is a rear plan view thereof;

FIG. 4 is a first side view thereof;

FIG. 5 is a second side view thereof;

FIG. 6 is an enlarged top view thereof; and,

FIG. 7 is an enlarged bottom view thereof.

The broken lines showing in the drawings are included for the purpose of illustrating portions of the multi-lifting cold & heat beauty device and form no part of the claimed design.
